UNITED STATES PATENT OFFICE.

PETER SCHIFFLER, OF AACHEN, GERMANY, ASSIGNOR TO MATHIAS SCHIFFLER, OF AACHEN, GERMANY.

PILE-PLANKING OF ROLLED IRON.

1,085,492.

Specification of Letters Patent.

Patented Jan. 27, 1914.

Application filed September 24, 1912. Serial No. 722,115.

To all whom it may concern:

Be it known that I, PETER SCHIFFLER, engineer, a subject of the King of Prussia, residing at No. 10 Stephanstrasse, Aachen, in the Kingdom of Prussia, Empire of Germany, have invented certain new and useful Improvements in Pile-Planking of Rolled Iron; and I do hereby declare the following to be a full, clear, and exact description of the invention, such as will enable others skilled in the art to which it appertains to make and use the same.

The object of the present invention relates to a pile-planking made of rolled sections which are so adapted as to be combined to a trough-shaped or scalariform wall of great resisting force.

The Figures 1-4 of the annexed drawing show cross-section views through such a planking in different representation-forms.

According to Fig. 1 the pile-planking consists of approximate S-shaped sections equal to one another which form a wall or planking of a trough-shaped cross-section, while in Fig. 2 a similar wall is formed by two different sections or profiles. In accordance with Fig. 3 a scalariform pile-planking is formed of Z-shaped sections which are exactly like one another, while in Fig. 4 two Z-shaped sections having differently formed ends, serve for the producing or manufacturing of the same planking.

In all representations the connecting places of the pile-planking are situated within its symmetrical axis, whereby the work of ramming is facilitated. In spite of this, the weakening of the wall caused by the guiding places, is only slight, as between two interrupted slanting walls, a full slanting wall is always arranged. Especially, the pile-planking according to Figs. 3-4 offers the advantage that the pointed edges of the planks exert a wedge-like effect against outer pressure. If therefore any concussion or force works or operates on the pointed outer edge of the plank, the same is directly divided into the two directions of the slanting walls and is then transferred to the abutment of the back wall.

Each of the planks comprises an approximately Z-shaped body portion 5 comprising a long member 10 having angular extensions

11 thereon. Carried by these extensions of the body portion are the means for interlocking the planks to form a structure. 55 Upon one end of the plank is formed a peculiarly shaped head 6, provided with an outwardly flaring shoulder 7. This head 6, is adapted to be inserted into a socket 8, carried by another one of the planking units. 60 This socket is formed to make a sliding fit for the head 6, and is provided with an inwardly turned member 9, which engages the shoulder 7, on the head 6. These interlocking portions of the planking units are placed 65 at the abutting ends of the planking units. The units may be provided with two sockets, one at each edge, or they may be provided with two heads or a head and a socket as desired. These units are slid one into the 70 other, the socket of one member receiving the head of the other member. Thus unfavorable working strains or spans in the plank-cross-section are avoided.

Having thus described my invention, what 75 I claim is:—

1. A metallic sheet piling comprising a plurality of detachable planking units, each of the units consisting of a bar bent to form a relatively long portion, a plurality of relatively shorter extensions oppositely disposed with relation to said longer portion and at angles thereto, interlocking fastening means carried by said shorter portions, said interlocking means comprising sockets formed 80 with shoulders and heads adapted to be inserted in the sockets.

2. In a metallic sheet piling, the combination with a plurality of separable units, of fastening means carried by said units, said fastening means lying in the same plane, a plurality of relatively short angularly disposed extensions adjacent each of said fastening means, a relatively longer member connecting said shorter extension said member being oppositely and angularly disposed relative thereto.

In testimony whereof I have signed my name to this specification in the presence of two subscribing witnesses.

PETER SCHIFFLER.
